UNITED STATES PATENT OFFICE.

HUGH E. LONGINO, OF MAGNOLIA, ARKANSAS.

TONSILLOTOME.

Application filed June 24, 1921. Serial No. 480,185.

To all whom it may concern:

Be it known that I, HUGH E. LONGINO, a citizen of the United States, residing at Magnolia, in the county of Columbia and State of Arkansas, have invented certain new and useful Improvements in Tonsillotomes, of which the following is a specification.

This invention relates to improvements in tonsillotomes.

In the use of the ordinary tonsillotome the root tissues of the tonsil are severed, usually by a wire snare, and are temporarily left unbound with the result that the operation is ordinarily attended with the loss of considerable blood. It is therefore the primary object of the present invention to provide a tonsillotome embodying means whereby tissues may be readily and conveniently tied or bound in a secure manner before being severed so that the operation will not result in the loss of any appreciable amount of blood, will be less dangerous to perform, and will permit of a more thorough subsequent examination of the throat at the leisure of the surgeon.

More specifically the present invention has as its object to provide in connection with a tonsillotome embodying a wire snare, means for the support of a looped ligature in such a manner that after the tonsil to be removed has been passed through the lumen of the instrument, the ligature may be pulled upon and automatically tied and knotted about the tissues at the base of the tonsil and remain tied to said tissues even after removal of the instrument from the mouth cavity, so that not only is loss of blood prevented, but furthermore the severed tissues may be left without attention temporarily and until the surgeon is prepared to make his further inspection and otherwise complete the operation.

A further object of the invention is to so construct the instrument that the ligature to be employed may be readily threaded therethrough, tied in a slip knot, and provided with a loop arranged in a concealed manner within the lumen of the instrument.

A further object of the invention is to provide novel means for retaining the ligature loop within the lumen of the instrument and in such position that it will not interfere with the loop of the wire snare by the contraction of which the tonsil tissues are to be severed.

In the accompanying drawing:

Figure 1 is a plan view of a tonsillotome constructed in accordance with the present invention;

Figure 2 is a side elevation of the instrument;

Figure 3 is a vertical longitudinal sectional view therethrough;

Figure 4 is a similar view in detail through the lumen end of the instrument.

Figure 5 is a horizontal sectional view taken substantially on the line 5—5 of Figure 4;

Figure 6 is a view similar to Figure 5, taken substantially on the line 6—6 of Figure 4.

The instrument embodying the invention comprises a shank which is indicated in general by the numeral 1 and which is provided with a longitudinally extending bore 2. The shank is also provided upon its upper side with a tubular guide indicated by the numeral 3, the bore of this guide being indicated by the numeral 4. At its forward end the shank 1 is provided with a lumen indicated in general by the numeral 5 and of the usual elliptical form, the lumen being disposed with its major axis transversely of the axis of the shank as illustrated in Figures 1, 5 and 6, and the opening of the lumen being indicated by the numeral 6. At the juncture of the forward end of the shank with the rear side of the lumen 5, the shank is broadened in a forward direction as indicated by the numeral 7 and this broadened portion is flat upon its opposite sides and its surfaces merge with the corresponding surfaces of the lumen 5. As clearly shown in Figure 6 of the drawing, the bore 2 of the shank 1 is gradually increased in width or flared throughout that portion of its length which extends through the broadened portion 7 of the shank and as indicated by the numeral 8, and the wall of the lumen 5 is formed in its inner side with a circumferential groove or channel 9 the ends of which communicate with the flared end 8 of the bore 2. The numeral 10 indicates a wire snare and the loop of this snare is indicated by the numeral 11 and is normally disposed within the groove or channel 9, the sides of

the loop extending along the side walls of the widened portion 8 of the bore 2 as best shown in Figure 6 of the drawing, so that when the instrument is prepared for use, 5 the loop or bight of the snare will be substantially completely housed within the channel 9 and flared end 8 of the bore 2 and no portion thereof will extend into the opening of the lumen 5 to interfere with the introduction of the tonsil through the said opening.

The ends of the snare 10 are led rearwardly through the bore 2 and are connected to a stem 12 which in turn is connected 15 to a lug 13 formed upon one end of a sleeve 14 which is provided with finger holds 15, the sleeve 14 being slidably fitted upon the rear end of the shank 1 of the instrument, and the lug 13 projecting slidably through 20 a slot 16 formed in this portion of the said shank. A thumb hold 17 is provided upon the rear end of the shank 1 and it will now be understood that by engaging the thumb in the hold 17 and the finger in the holds 15, 25 the sleeve 14 may be pulled rearwardly upon the shank of the instrument so as to contract the loop or bight of the snare 10 and thus cause the same to sever the root tissues of a tonsil which has been engaged through the 30 opening 6 of the lumen 5.

In addition to the channel 9, the wall of the opening 6 of the lumen 5 is formed with a channel 18 which extends circumferentially thereof as best shown in Figures 4 35 and 5 of the drawings and which communicates with the forward end of the bore 4, this bore being formed inwardly of its forward end with a restricted or shouldered portion 19 for a purpose to be presently explained. The numeral 20 indicates a ligature of cat gut or silk which is threaded through the bore 4, provided with a slip knot 21, and at the same time formed into 40 a loop 22 which loop is disposed to lie within the channel 18 as shown in Figure 4 of the drawings, the slip knot 21 being received within the forward end of the bore 4 and resting against the shoulder portion 19 of the bore. The other end of the ligature is 45 carried beyond the rear end of the tubular guide 3 where it may be conveniently grasped for a purpose to be presently pointed out.

In order that the loop 22 may be retained 55 within the channel 18 and supported out of the way of the loop 11 of the snare 10, resilient wire fingers 23 are arranged at the opposite sides of the lumen 5 within the opening thereof and are secured at their forward ends in any suitable manner, as at 60 24, to the inner surface of the wall of the lumen. These fingers 23, from their attached ends 24, are extended obliquely longitudinally of the wall of the lumen 5 and lie snugly against said wall by their inher-

ent resiliency. Likewise it will be observed that the fingers extend across the channel 18 and that the free extremities of the fingers terminate approximately in the plane of the upper side of the lumen 5. In engaging 70 the loop 22 within the channel 18, the sides of the loop are slipped behind the resilient fingers 23 and the loop is disposed within the said channel, being retained therein by the said fingers 23 and thus supported clear 75 of the loop 11 of the snare. It will be understood however that the fingers 23, because of their resiliency, will be adapted to be sprung inwardly when the loop 22 is contracted and as the loop slips over these fingers. 80

In the use of the instrument, the same is first prepared for use by arranging the loops 11 and 22 within the respective channels in the lumen of the instrument after which the 85 instrument is introduced into the throat with the side at which the ligature loop is located presented next to the base of the tonsil, and the tonsil is engaged through the opening of the lumen 5. When all of the 90 tonsil has been passed through the lumen, the wire loop 11 is contracted until it has been drawn somewhat tightly about the tissues at the base of the tonsil but not so tightly as to cut the tissues. The end of the 95 ligature which extends beyond the rear end of the tubular guide 3 is then grasped and pulled so as to tie the ligature tightly in a knot about the said tissue. The loop of the snare 10 is then further contracted so as to 100 sever the tissue and thus clip off the tonsil. The ligature is then released and the instrument may be removed from the throat and slipped off from the ligature leaving the same securely tied to the tissue adjacent the 105 point of severance. As the ligature is tightly tied about the tissues, there can be no appreciable loss of blood, and the throat may be inspected at leisure. Of course the surplus length of ligature will be clipped 110 off but this may be deferred for as long a time as desired.

It will be understood that while in the drawing means is illustrated for supporting a ligature loop in juxtaposition to a 115 snare loop, it will be within the province of the invention to employ the ligature loop supporting means in connection with some other type of means for severing the tonsil tissues. At the same time there are peculiar 120 advantages resulting from the combination of the two loop supporting means within the lumen of the instrument.

Having thus described the invention, what is claimed as new is:

1. In a tonsillotome, in combination, means for severing tissue, and means for the support of a ligature loop to be tied about the tissue. 125
2. The combination with a tonsillotome, 130

of means for supporting a looped ligature in juxtaposition to the tonsil-engaging means thereof.

3. In a tonsillotome having a lumen, means within the lumen for supporting a snare loop, and means within the lumen for supporting a ligature loop to be tied about the tissue severed by the snare loop.

4. In a tonsillotome, in combination, means for severing tissue, means for the support of a ligature loop to be tied about the tissue, and an abutment for the loop knot of the ligature.

5. In a tonsillotome, in combination, means for severing tissue, a lumen, a ligature guide, and means within the lumen for supporting a loop formed at the end of a ligature engaged in the guide.

6. In a tonsillotome having a lumen and a ligature guide, means within the lumen for supporting a loop formed at the end of a ligature engaged in the guide, and an abutment for the knot of such a loop.

7. In a tonsillotome having a lumen, a ligature guide including a knot abutment arranged in juxtaposition to the lumen, the wall of the lumen being provided with a channel to receive a loop formed in a ligature passed through the guide, and resilient means retaining the ligature loop within the channel.

8. In a tonsillotome having a lumen, a ligature guide including a knot abutment arranged in juxtaposition to the lumen, the

wall of the lumen being provided with a channel to receive a loop formed in a ligature passed through the guide, and resilient means retaining the ligature loop within the channel, the said means comprising fingers disposed obliquely across the channel.

9. In a tonsillotome, the combination with a lumen and a snare loop arranged therein, of means within the lumen for the support of a looped ligature in substantial parallelism to the snare loop.

10. In a tonsillotome, the combination with a lumen and a snare loop arranged therein, of means within the lumen for the support of a loop formed in a ligature which is to be tied about the tissue adjacent the point of severance, and an abutment in juxtaposition to the lumen against which the knot in the ligature which provides the loop, may engage.

11. In a tonsillotome, in combination, a lumen, a snare loop arranged therein, means for contracting the snare loop, a ligature having a knotted end through which the length of the ligature is threaded to provide a loop, means within the lumen supporting the ligature loop in substantial parallelism to the snare loop, and an abutment for the knot of the ligature loop in juxtaposition to the lumen.

In testimony whereof I affix my signature.

HUGH E. LONGINO. [L.S.]
